DESIGN FOR A CUFF LINK

Francesco Collura, New York, N. Y.

Application January 17, 1945, Serial No. 117,477

Term of patent 3½ years

(Cl. D17—2)

To all whom it may concern:

Be it known that I, Francesco Collura, a citizen of the United States, residing at New York city 22, county and State of New York, have invented a new, original, and ornamental Design for a Cuff Link, of which the following is a specification, reference being had to the accompanying drawing, in which the figure is a perspective view of a cuff link showing my new design.

I claim:

The ornamental design for a cuff link, as shown.

FRANCESCO COLLURA.
